(57) **CLAIM**

I claim the ornamental design for a thermal imaging camera, as shown and described herein.

DESCRIPTION

FIG. 1 is a top, front and left side perspective view of a thermal imaging camera;

FIG. 2 is a front elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan thereof; and,

FIG. 8 is a top, rear and right side perspective view thereof.
